SHIFTING MECHANISM FOR TIME
RECORDERS

Edward G. Watkins and James A. Dell, Gardner,
Mass., assignors to Simplex Time Recorder
Company, Gardner, Mass., a corporation of
Massachusetts

Application June 2, 1936, Serial No. 83,128

1 Claim. (Cl. 200—106)

This invention relates to machines for making a printed record of an employee's working hours, usually upon a weekly time card. A common form of card provides separate vertical columns for different "In" and "Out" records, which in turn necessitates periodical relative transverse adjustment between the card holder and the printing mechanism in order that the different records may be correctly located in their assigned columns. More commonly, the card holder or chute is shifted transversely relative to the printing mechanism, which latter remains in a fixed position.

It is the general object of our invention to provide improved means for accomplishing this transverse relative adjustment between the card holder or chute and the printing mechanism at predetermined time intervals.

A further object is to provide means to prevent any possibility of over-feed of the moving part.

A preferred form of our invention is shown in the drawings, in which

Fig. 1 is an end elevation of our improved shifting mechanism;

Fig. 2 is a rear view, looking in the direction of the arrow 2 in Fig. 1;

Fig. 3 is a partial plan view, looking in the direction of the arrow 3 in Fig. 1;

Fig. 4 is a partial front elevation, looking in the direction of the arrow 4 in Fig. 3;

Fig. 5 is a detail sectional rear elevation, taken along the line 5—5 in Fig. 1;

Fig. 6 is a detail sectional view, taken along the line 6—6 in Fig. 2; and

Fig. 7 is a detail front elevation, looking in the direction of the arrow 7 in Fig. 1.

Referring to the drawings, we have embodied our invention in a construction in which a card holder or chute C (Figs. 1 and 4) is shifted transversely relative to printing type wheels W (Fig. 4). The card chute C is transversely slideable on a fixed rod 10 and is connected to a rack bar 12 having teeth 13 engaging the teeth of a mutilated pinion 14, mounted on a sleeve 15 which is rotatable on a cross shaft 16. A collar 17 (Fig. 3) is fixed on the shaft 16 and has a lug 18 engaged by a pin 19 projecting outward from the sleeve 15. A lost motion connection is thus provided between the pinion 14 and the cross shaft 16. A spring 20 is connected to the card chute and holds the pin 19 (Fig. 3) in yielding engagement with the lug 18.

A ratchet wheel 22 (Fig. 2) is secured to the cross shaft 16 and is engaged by a feed pawl 23 pivoted at 24 to a bracket 25 mounted on a ver-

tical slide bar 26. The bar 26 is slotted at its upper end, as indicated at 27 in Fig. 1, and is slideable on a fixed stud 28, the upper end of the slot 27 acting as a stop to limit downward movement of the bar.

The lower portion of the bar 26 is slideable in a recessed guide 29 (Fig. 2), and a spring 30 yieldingly holds the bar normally in its lowermost position. A stud 31 on the bar 26 limits swinging movement of the pawl 23 counter-clockwise as viewed in Fig. 2, and a stud 32 on the bar 26 limits movement in the opposite direction under the influence of a spring 33.

A bracket 35 (Fig. 2) on the bar 26 is loosely connected at 36 to the outer end of an arm 37 connected at 38 to the outer end of an arm 37 swinging about a fixed pivot 38. A forked link 40 (Fig. 7) operatively connects the arm 37 to the upper end of a solenoid plunger 41, slideable vertically in a solenoid coil 42. When the solenoid is energized as will be hereinafter described, the plunger 41 is moved upward and acts through the link 40 and arm 37 to raise the bar 26 against the tension of the spring 30. As the bar is raised, the pawl 23 swings clockwise under the tension of the spring 33, into position to engage the next tooth of the ratchet wheel 22.

As soon as the solenoid circuit is broken, the spring 30, assisted by gravity, quickly restores the parts to their initial lowered position and advances the ratchet wheel 22 one space.

It will be noted that when the parts are in the normal lowered position indicated in Fig. 2, the enlarged head of the pawl 23 is interposed between the ratchet wheel 22 and the stop 31 in such manner that further forward or anti-clockwise movement of the ratchet wheel (as viewed in Fig. 2) is effectively prevented. At the same time backward rotation of the cross shaft 16 is prevented by a second ratchet wheel 45 (Fig. 5) fixed to the shaft and engaged by a pair of holding pawls 46, each of which is pressed against the wheel 45 by a spring 47 (Fig. 1).

A ring 50 (Fig. 1) is mounted on the sleeve 15 alongside the mutilated pinion 14 and is rotatable with the pinion and sleeve. The ring 50 has a projection 51 (Fig. 4) adapted to be engaged by a stud 52 in the rack bar 12 as the rack bar and card chute complete their return movement to the left after release by the mutilated pinion.

In order to close the solenoid circuit at the desired time intervals, we provide a timing disc 55 (Figs. 2 and 6) mounted on a shaft 56 actuated by suitable time mechanism and making one complete revolution in twenty-four hours.

This timing disc 55 has an inner series of holes 57 and an outer series of tapped holes 58.

Clips 60 are provided for attachment to the timing disc 55. Each clip has a stud 61 (Fig. 2) 5 at the outer end and a second stud 63 at the inner end, the stud 63 being on the opposite side of the clip and being adapted to be inserted in one of the inner series of openings 57. Each clip 60 also has a segmental slotted portion 64 10 through which a clamping screw 65 may be inserted in one of the tapped holes 58. With this construction, clips 60 may be secured to the timing disc 55 in any desired angular spacing.

An arm 70 (Fig. 6) is secured to a rock shaft 15 71 mounted in fixed bearings in the recorder frame, which arm 70 is provided with an offset end portion 72 extending into the path of the studs 61 in the outer ends of the clips 60.

A second arm 74 (Figs. 2 and 6) is mounted 20 on the rock shaft 71, and a spring 75 is connected between the arm 74 and a fixed stud 76. A third arm 80 is also secured to the rock shaft 71 and has a horizontally offset lower end 81 (Fig. 2) which engages the rear face of a post 84 (Fig. 1) 25 pivoted at its lower end in a fixed bearing 85.

A stop pin 86 (Fig. 1) limits forward movement of the swinging post 84, and a cross-pin 87 in a stud 88 limits rearward movement of the post. A spring 89 on the stud 88 yieldingly 30 presses the post 84 rearward against the offset portion 81 of the arm 80. A pawl 90 is pivoted at 91 on the post 84 and is yieldingly pressed downward by a spring 92.

The circuit through the solenoid coil 42 comprises a line wire 100 (Fig. 1) connected to one 35 terminal of the coil 42 and a wire 101 connecting the second terminal of the coil to a cross-plate 102 (Fig. 2) mounted on a fixed bar of non-conducting material 103. The cross plate 102 is connected to a flat metal spring 104, also supported on the non-conducting bar 103, said 40 spring having a contact element 105 at its upper end.

The contact element 105 is positioned for engagement with a second contact element 106 45 mounted on a cross-plate 107 which in turn is supported on a fixed block 108 of hard rubber or other non-conducting material. A second line wire 110 is connected to the cross plate 107.

A plate 112 (Figs. 1 and 2) of non-conducting material is clamped to the upper end of the spring 104 and extends upward therefrom. At 50 its upper edge the plate 112 is provided with a ledge 113 which projects into the path of a shoulder 114 on the lower edge of the pawl 90.

When the post 84 and pawl 90 are moved forward from normal rearward position, the shoulder 114 engages the ledge 113 and pushes the contact element 105 forward into engagement 55 with the contact element 106, thus completing the solenoid circuit and causing upward movement of the solenoid plunger 41.

An arm 120 (Fig. 1) is fixed to the upper end of the solenoid plunger 41 and extends rearward 60 thereof. The pawl 90 has an end portion 122 extending forward over the arm 120. As the plunger 41 moves upward, the arm 120 engages the end portion 122 of the pawl 90 and moves the pawl upward so that the shoulder 114 is released 65 from the ledge 113, thereby permitting the spring 104 to move rearward, and break the solenoid circuit.

Upward movement of the plunger 41 is limited by a collar 125 (Fig. 1) and cushioning washer 70 75 126 both secured to the lower end of the plunger.

Having described the details of construction of our improved shifting mechanism, it is believed that the method of operation will be readily understood.

Each time that a stud 61 in a timing clip 60 5 engages and depresses the arm 70 on the rock shaft 71, the arm 80 is moved rearward, thus permitting the post 84 to swing rearward and resetting the pawl 90, at the same time tensioning the spring 75.

When the stud 61 clears the end portion 72 of the arm 70 with which it has engaged, the spring 75 restores the parts to normal position and pushes the post 84 forward, thus closing the circuit between the contacts 105 and 106.

The solenoid then operates to lift the sliding bar 26 and the feed pawl 23 upward and to tension the spring 30, at the same time lifting the pawl 90 so that the solenoid circuit will be promptly broken.

As soon as the circuit is broken, the spring 30, assisted by gravity, moves the bar 26 and pawl 23 downward, advancing the ratchet wheel 22 one space only. The enlarged head of the pawl 23 then cooperates with the stud 31 to prevent 25 overfeed.

Each time the solenoid operates, the pinion 14 is moved clockwise one space (as viewed in Fig. 4) and shifts the card chute C one space to the right. At the next advance movement of the 30 pinion 14 after the card chute has been shifted to its extreme right-hand position, the mutilated portion of the pinion will be moved to a position to clear the teeth 13 of the rack bar 14, thus permitting return movement of the card chute 35 by the spring 20.

As this return movement to the left is completed, the stud 52 (Fig. 4) engages the projection 51 on the collar 50, so that the next angular advance movement of the pinion will again shift 40 the card chute and will also cause the pinion teeth to reengage the teeth on the rack bar.

The lost motion connection between the pinion 14 and the cross shaft 16 permits manual yielding movement of the card chute against the tension of the spring 20 for making certain irregular registrations.

Having described our improved shifting mechanism, it will be seen that we have provided for instantaneous and accurate shifting movements 50 of the card chute at predetermined intervals, under the control of the time mechanism but operated from an external source of power, so that the load on the time mechanism is extremely slight. Furthermore, we have provided a construction by which the timing of the shifting movements may be very easily rearranged as often as desired by merely resetting the clips on the timing device.

While we have illustrated our invention as embodied in a machine in which the card chute is shifted transversely and the printing mechanism has no transverse movement, which arrangement per se is old in the patent to Campbell No. 1,201,555, issued October 17, 1916, our invention 65 also contemplates the alternative arrangement of transversely movable printing mechanism and a transversely fixed card chute, also shown to be old in the patent to Hawley, No. 917,761, issued April 13, 1909.

Having thus described our invention and the advantages thereof, we do not wish to be limited to the details herein disclosed, otherwise than as set forth in the claim, but what we claim is:

In a time recorder having a shiftable element, 75

means for shifting said element bodily including an electro-magnetic operating device, an electric circuit for said device and relatively movable contacts in said circuit, that improvement which 5 comprises the combination therewith of an actuating device effective to move one of said contacts to close said circuit, means to so move said actuating device, automatic means to disengage said actuating device immediately after 10 the circuit is closed and before said moving means and said actuating device are withdrawn, reset-

ting devices, and automatic time-controlled means effective to thereafter withdraw said moving means and thereby permit said resetting devices to place said actuating device in operative relation to the contact actuated thereby, said time-controlled means releasing said moving means at a predetermined later time so that said moving means will move said actuating device to again close said circuit.
